AMUSEMENT DEVICE

Guy R. Lanman, El Reno, Okla.

Application March 8, 1944, Serial No. 525,586

4 Claims. (Cl. 272—54)

1

This invention relates to amusement devices, and its general object is to provide a device of the teeter board type, or in other words a seesaw, in which the beam or board is held for rocking movement in a fixed path against casual removal or displacement relative to its supporting means, as well as to prevent the ends of the board from contacting or hitting the ground, thus it will be seen that the board is equally balanced relative to its support, at all times, and danger of injury to the legs and feet of the rider on the down end of the board and/or the rider on the upper end thereof, being thrown from the board, is reduced to a minimum, due to the elimination of the sudden jar brought about by boards now in general use hitting the ground, therefore my device is extremely safe for use by small children, yet will produce much amusement and fun.

A further object is to provide a teeter board amusement device that is simple in construction, inexpensive to manufacture and extremely efficient in operation, use and service.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:

Figure 1 is a side view of the device which forms the subject matter of the present invention.

Figure 2 is a transverse sectional view taken through the board and illustrates other parts in section and in elevation.

Figure 3 is a sectional view taken approximately on line 3—3 of Figure 2, looking in the direction of the arrows.

Figure 4 is a sectional view taken approximately on line 4—4 of Figure 2, looking in the direction of the arrows.

Figure 5 is a fragmentary bottom plan view.

Figure 6 is a perspective view of the board attaching and rocking frame, looking toward the top thereof.

Figure 7 is a perspective view of the axle or fixed bearing for the frame.

Referring to the drawing in detail, it will be noted that my device in the form shown includes a pair of spaced parallel tubular uprights or standards 1 that are suitably anchored in the ground, as shown in Figure 1, and removably and

5 fittedly mounted in the upper ends of the uprights, are depending nipples 2 that are formed on caps 3, the latter each being provided with an upper arcuate seat 4. The seats open toward each other, and the outer ends thereof are closed by walls 5 having inclined outer faces, and the nipples are formed on the caps in a manner to provide abutment shoulders that rest upon the upper ends of the uprights, as clearly shown in

10 Figure 2.

Bridging the caps and mounted in the seats 4 is a tubular axle 6 that is fixed to the caps by bolt and nut connections 7, the bolts extending through blocks 8, the axle and the bottom walls 15 of the cap, and the blocks are mounted within and at the ends of the axle, as well as are provided with lower faces shaped to follow the transverse curvature of the axle, as best shown in Figures 3 and 4. Fixed to the under faces of 20 the axle is a pair of spaced arcuate strips 9 having bumper blocks 10 formed on the upper ends thereof for a purpose which will be later described, and the blocks have upper faces that are inclined downwardly from their juncture with the axle. Each block has a hole in the upper face thereof and removably mounted in the hole is a stud 11 that is formed or otherwise secured to the bottom of a shim 12. Shims of various thicknesses may be used to vary the height of 30 the bumper elements, as will be apparent upon inspection of Figure 4.

The board or beam is indicated by the reference numeral 13 and is of the usual flat elongated formation. Fixed by bolt and nut connections to the under side of the board for disposal midway the ends thereof is an open rectangular frame 14 that has webs 15 formed on and depending from the side members 16 thereof, and formed on and bridging the webs is a 40 semicylindrical bearing 17 that fits and is mounted on the axle 6 for rocking movement of the board.

The bearing 17 is held on the axle by semi-circular bearing bands 18 having ears formed 45 on the ends thereof, and the ears are secured to the flat under faces of the webs by bolts 19. Formed on and extending laterally from the bearing 17 for disposal flush with the longitudinal edges thereof, are two pair of diametrically opposed lugs 20, and the abutment or bumper elements that are fixed to the axle are arranged in the path of the lugs 20 to limit rocking movement of the board. The board is of a length relative to the height of the uprights, so that the ends 55 thereof will not contact or hit the ground.

A housing of sheet metal or the like is disposed about the frame and axle, and the housing includes a semi-cylindrical wall 21 having outwardly directed flanges 22 formed on the longitudinal edges thereof, the flanges being fixed to the board upon opposite ends of the frame, and the housing also includes side walls 23 having openings therein through which project the ends of the axle. It will be obvious that the housing not only protects the parts against dirt and dust, but provides a guard to prevent children from getting their fingers caught between the parts and particularly the abutting elements.

From the above description and disclosure of the drawing, it will be obvious that my device is extremely safe for small children, in that the board is not only held for rocking movement in a fixed path against casual removal or displacement relative to the axle, but injury to the feet and legs of the rider or the latter being thrown from the board is practically eliminated, and which frequently happens by the use of teeter boards of the type now in general use, as a result of a sudden jar brought about by the ends of the latter boards hitting the ground.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:

1. An amusement device comprising upright supporting means, an axle secured to the upper end of the supporting means, a flat elongated board, a frame fixed to the under side of the board midway its ends, an elongated bearing secured to and bridging the frame and mounted on the axle for rocking movement of the board, lugs formed on said bearing, abutment means having stud receiving openings therein secured to the axle, removable shims having studs formed integral therewith adapted to be received in said stud receiving openings, said shims being disposed in the path of the lugs to limit rocking movement of the board, and the latter being of such a length relative to the height of the supporting means and the angle of the abutment means to the horizontal being such as to prevent the ends of the board from contacting the ground.

2. An amusement device comprising a pair of spaced parallel tubular uprights having their lower ends anchored, a cap mounted on the upper end of each upright and formed with an arcuate seat, a wall closing the outer side of the seat and the inner sides of the seats being open and directed toward each other, an axle secured in said seats and bridging the same, a flat elongated board, a frame fixed to the under side of the board midway its ends, an elongated bearing secured to and bridging the frame and mounted on the axle for rocking movement of the board, lugs formed on said bearing and extending from diametrically opposite sides thereof, abutment means secured to the axle and including block-shaving upper faces inclined downwardly from the axle, the upper faces of said blocks having stud receiving openings therein, the stud receiving openings of said faces adapted to receive studs formed integral with removable shims, said shims being disposed in the path of the lugs

to limit rocking movement of the board, and the latter being of such a length relative to the height of the uprights and the angle of the abutment means to the horizontal being such as to prevent the ends of the board from contacting the ground.

3. An amusement device comprising a pair of spaced parallel tubular uprights having their lower ends anchored, a cap for each upright and including a depending nipple mounted in the upper end thereof, an arcuate seat in the top of the cap, a wall closing the outer side of the seat and the inner sides of the seat being open and directed toward each other, a tubular axle fixed in said seats and bridging the same, a flat elongated board, a rectangular frame fixed to the under side of the board midway its ends, a semi-cylindrical bearing secured to and bridging the frame and mounted on the axle for rocking movement of the board, lugs formed on said bearing and extending laterally therefrom, abutment means having stud receiving openings therein secured to the axle, removable shims having studs formed integral therewith, said studs adapted to be received in said stud receiving openings, said shims being disposed in the path of the lugs to limit rocking movement of the board, and the latter being of such a length relative to the height of the uprights, and the angle of the abutment means to the horizontal being such as to prevent the ends of the board from contacting the ground.

4. An amusement device comprising a pair of spaced parallel tubular uprights having their lower ends anchored, a cap mounted on the upper end of each upright and formed with an arcuate seat, a tubular axle mounted in the seats and fixed to the caps in bridging relation thereto, a flat elongated board, a rectangular frame fixed to the under side of the board midway its ends, webs formed on and depending from the side members of the frame, a semi-cylindrical bearing fixed to the webs and bridging the same and mounted on the axle for rocking movement of the board, diametrically opposed lugs formed on said bearing, abutment means including strips fixed to the under side of the axle, blocks having stud receiving openings therein secured to the ends of the strips, removable shims having studs formed integral therewith, said studs being received in said stud openings of the blocks for disposal in the path of the lugs to limit rocking movement of the board, a housing secured to the under side of the board and disposed about the axle, side walls included in the housing and having the ends of the axle extending therethrough, and said board being of such a length relative to the height of the uprights, and the angle of the abutment means to the horizontal being such as to prevent the ends of the board from contacting the ground.
